A. LARROWE.

Sleigh.

No 22295.

Patented Dec. 14. 1858.

UNITED STATES PATENT OFFICE.

A. LARROWE, OF COHOCTON, NEW YORK.

SLED-BRAKE.

Specification of Letters Patent No. 22,295, dated December 14, 1858.

To all whom it may concern:

Be it known that I, ALBERTUS LARROWE, of Cohocton, in the county of Steuben and State of New York, have invented certain new and useful Improvements in Brakes for Sleds or Sleighs; and I do hereby declare that the following is a full and exact description thereof, reference being had to the accompanying drawings and to the letters 10 of reference marked thereon.

In the drawings, Figure 1 is a perspective view.

To enable others skilled in the art to make and use my invention I will describe 15 its construction and operation.

The nature of my invention consists in the manner of operating a self acting brake for sleighs, sleds or sledges for the purpose of stopping them.

20 In the construction of my invention, (a) is the rod for operating the scrapers. (b) the doubletree to which the horses or oxen are attached, and is attached to a rod (a) by a bolt (b'), passing through it. (c) the 25 lever extending across the sled and up above the top of the same to which is attached the rod. (c') and (d) are the arms of said lever at nearly right angles with the said lever (c) and is a part of it thus bent, or, if 30 more convenient may be made separately. (e) the scrapers which are, when operated thrown down below the runner of the sled to catch into the ice, snow, or ground. (f) a 35 rod extending from the scrapers (e) to a staple in the knee or beam of the sled into which it is fastened by a hook and through which it slides. A, the sled. B, the guide pole. C, the yoke bar to which the horses are attached in front, and which slips over 40 the guide pole.

In the operation of my invention, the team is hitched behind to the bar (b), and in front are attached to the breast yoke C, and as the beam draws forward, the bolt 45 (b') with rod (a) is drawn forward thus drawing the lever (c) into a vertical position, and thus raising up the scrapers above the bottom of the runners out of the way so that they will not catch in the ice or snow, &c.; 50 but, when it becomes necessary to lock the

sled the beam is made to hold back, then the breast yoke is brought to bear against the raised end of rod (a) causing it to slide back which causes the bolt to slide in the mortise, and pushes back and down the lever 55 (c) which operates on the scrapers (e) throwing them down below the runners of the sled, causing them to catch into the ice or snow, &c., and at once retarding the sled, as they are held firmly in this position by 60 the rods (f). If I wish to back the sled, as the pressure is brought to bear against the rear side of scrapers (e) they will move forward, since the rod (f) can slide forward in the staples, thus offering no resistance in 65 backing. When the beam starts forward, the rod (a) is drawn forward as already described and the scrapers are lifted up out of the way. The rod (a) is let into the pole even with the top surface, the doubletree 70 is fastened to a bolt passing through both the doubletree and rod, and when the draft is on the sled, the bolt (b') is drawn up against the front end of the mortise, and this is the point of draft instead of the lever (c); 75 the doubletree can vibrate on the bolt and accommodate itself to the irregular draft of the team.

The advantages of my invention are, that, 80 my scrapers are always self acting, and will be at all times efficient in stopping the sled, and not prevent backing, and when not required are lifted out of the way by the action of the machine alone. The scrapers (e) operate on a hinge as seen at (e') formed by 85 joining it to the right angled end of the lever (c); at the lower end the scraper operates on a hinge joint formed by its connecting with rod (f). By the use of these hinged joints the scraper is made to operate at all 90 times in one given position, except when the sled is pushed backward, then it simply slips forward swinging only on the joint (e') as the lower end is pressed forward.

It will be seen that the rod (a) has a joint 95 (a') at the point where the guide pole is attached to the sled, for the purpose of allowing the pole to be raised. The raising of the pole in holding the sled assists the power of the brake in connection with the 100

rod (α) when it is forced back by the team. I place my rod on top of the pole, by this an increase of power is obtained, by the pole raising in holding back the sled.

- 5 What I claim as new and desire to secure by Letters Patent is—
The arrangement of lever c scrapers e and

rods f , operating as described, for the purpose of a self acting brake and self relieving in backing the sled as set forth.

ALBERTUS LARROWE.
